DESIGN FOR A RING

Richard J. Blooston and Thomas K. Kelly, Jr.,
Minneapolis, Minn.

Application April 29, 1937, Serial No. 69,048

Term of patent 3½ years

To all whom it may concern:

Be it known that we, Richard J. Blooston and Thomas K. Kelly, Jr., citizens of the United States, residing at Minneapolis, in the county of Hennepin and State of Minnesota, have invented a new, original, and ornamental Design for a Ring, of which the following is a specification, reference being had to the accompanying drawing, forming part thereof.

of a ring showing our new design; and Figure 2 is a side view thereof, a fragmentary portion only of the band being shown for convenience in illustration.

We claim:

The ornamental design for a ring, as shown and described.

RICHARD J. BLOOSTON.

THOMAS K. KELLY, JR.
